APPARATUS FOR CLEANING VEHICLES

William John Morison, Chelmsford, England

Application April 18, 1949, Serial No. 88,105
In Great Britain April 28, 1948

24 Claims. (Cl. 15—97)

1

This invention relates to apparatus for cleaning vehicles, and more particularly to the cleaning of vehicles, such as omnibuses, motor cars and the like, at a cleaning station.

Various proposals have heretofore been made to clean vehicles at a washing station having fixed pipes provided with nozzles by means of high-pressure and low-pressure jets of a cleansing fluid issuing from the nozzles. The present invention has for its main object to enable vehicles to be cleaned mechanically at a cleaning station in an improved manner, with or without the use of such jets, and another object is to provide an improved construction of vehicle-cleaning apparatus for that purpose.

It is another object of the invention to provide apparatus for carrying out a method of mechanically cleaning a vehicle at a cleaning station, comprising the steps of imparting a cleaning movement, preferably a rotary movement, to at least one wiper device mounted on a movable carrier, and moving the carrier vertically while the wiper device or devices is or are in motion in contact with the outside of the vehicle to be cleaned. In this way the vehicle can be dry-cleaned.

When wet-cleaning is required, the method comprises the further step of subjecting the surface of the vehicle to be cleaned, before, during or after the cleansing operation by means of the wiper device or devices, to the action of jets or spray of cleansing liquid movable vertically with the carrier.

It is another object of the invention to provide improved apparatus for mechanically cleaning a vehicle at a cleaning station, comprising in combination a carrier, at least one wiper device mounted thereon, means for imparting a cleaning, preferably rotary, motion to the wiper device or devices on the carrier, and elevator means for moving the carrier vertically in relation to the outside of the vehicle while the one or more wiper devices are in motion and in wiping contact with the outside of the vehicle.

Conveniently, the carrier has associated with it, and movable vertically with it, at least one delivery pipe for cleansing liquid having a plurality of nozzles spaced apart in the direction of length thereof for causing jets of liquid or spray to impinge on the outside of the vehicle.

The carrier is preferably of elongated formation, and a wiper device of the flat or bladed type, or more than one such wiper devices, may extend in the direction of length of the carrier.

Conveniently a frame constituting the carrier is formed as a guard having bearing brackets mounted on it in spaced relation one or more than

2

one shaft situated in the guard is journaled in said brackets, and one or more than one wiper device is carried by each shaft.

An electric motor or motors may be mounted on the carrier and arranged to rotate the wiper devices.

It is yet another object of the invention to provide apparatus for mechanically cleaning a vehicle at a cleaning station, comprising a carrier that is constituted by a frame, preferably of U-shape as viewed in plan, and has two side limbs arranged to lie at opposite sides of the vehicle and an end limb arranged to lie at an end of the vehicle, a plurality of shafts mounted one on each limb of the frame, each of which shafts has at least one wiper device mounted on it, means for imparting rotary motion to the shafts, and elevator means arranged to move the frame vertically while the wiper devices are in motion and in contact with the vehicle.

Each limb of the frame is preferably provided with a pipe having nozzles for delivering a cleansing liquid against the vehicle.

The frame may have two opposed limbs arranged to lie respectively at opposite sides of the vehicle, as above described, or at opposite ends of the vehicle and the frame may be adjustable to vary the separation of the two opposed limbs thereby to permit the apparatus to be used for cleaning vehicles of different widths or of different lengths. The frame may be of rectangular form and the two opposed limbs may be constrained for adjusting movement parallel to one another. The opposed limbs may be arranged for relative adjusting movement between two positions providing respectively two preselected distances of separation between the opposed limbs. This feature is of particular advantage in connection with the cleaning of omnibuses which are each of one of two standardised widths when omnibuses of each of these widths have frequently to be cleaned at the same cleaning station. The opposed limbs may be spring-urged relatively towards one another to a preselected position of lesser separation and may be arranged to be moved to, and held in, a preselected position of greater separation by an over-centred toggle mechanism.

When the apparatus set forth above is arranged under a superstructure, such as a roof of a garage or other building, the carrier is preferably suspended from the superstructure by two sets of suspension members, such as cables or ropes, running over sheaves or pulleys spaced apart in the direction of travel of a vehicle to be cleaned, which sets are attached to the carrier at opposite sides thereof.

These suspension members of the two sets may be brought together and carry a counterweight common to them all.

Driving means for raising and lowering the carrier preferably comprises a winding device driven by an electric motor, on which a suspension member is wound in opposite directions.

Provision is preferably made for automatically reversing the driving means when the carrier arrives at its upper and lower position.

When the driving means comprises an elevator electric motor arranged to drive a winding device to which the suspension members are connected, the reversing means preferably comprises contactor or like means arranged to reverse the elevator motor, and a limit switch that controls the contactor means and is operable by driver members movable with the suspension members.

Electrical equipment controlling the elevator motor and motors for rotating the wiper devices will be described hereinafter.

The reversing means may comprise manually-operable switch means and may be arranged to reverse the elevator motor when the carrier is at desired intermediate situations between its upper and lower end positions.

One embodiment of the invention and modifications of that embodiment will now be described by way of example, and not by way of limitation, with reference to the accompanying drawings wherein:

Figure 1 is a side elevation, partly in section, and partly broken away, showing one construction of vehicle-cleaning apparatus according to the invention.

Figure 2 is a plan view, partly broken away, of the carrier of the wiper devices shown in Figure 1.

Figure 3 is an end elevation of the carrier shown in Figure 2 as viewed from the right-hand side thereof.

Figure 4 is a vertical section taken through a limb of the carrier.

Figure 5 is a horizontal sectional detail view showing a counterweight, taken along 5-5 of Figure 1.

Figure 6 is a perspective view showing wiper devices on a scale larger than that of Figures 1 to 3, and

Figure 7 is a view showing a diagrammatic layout of the carrier, its suspension means and other devices associated therewith.

Figures 8 and 9 are respectively a diagram of an electrical equipment of the vehicle-cleaning apparatus, and a modification thereof.

Figure 10 is an under-plan view of a modified carrier which is adjustable so that one side limb may be moved to the position indicated in broken lines, and

Figures 11 and 12 are views of one end of the carrier shown in Figure 10 showing it respectively in two different positions of adjustment.

Like reference characters designate like parts throughout the several views.

Referring first to Figures 1 to 7, apparatus for cleaning a vehicle, such as an omnibus 10 indicated in broken lines, at a cleaning station or garage having a superstructure 12 constituted by a roof, shown broken away, an end wall 14, and guide members 16 on the ground or floor 70 for the vehicle-wheels, comprises a carrier constituted by a three-sided frame of U-shape, as viewed in plan, designated generally 18. This frame has two side limbs 20 and 22 arranged to lie at opposite sides of the vehicle 10, and an

end limb 24 arranged to lie at an end, preferably the rear end, of the vehicle. Each limb forms a guard of U-shape in vertical cross-section, and opens horizontally towards the space bounded by the limbs of the frame. In Figures 1 and 3, a bracing or tie member 26 is shown at the open end of the frame, which also has vertical struts 28 (see Figures 3 and 6) at its open inner sides.

10 A number of rotary wiper-devices, each designated generally 30, is mounted in the frame, several thereof being arranged in a row in each limb. As shown most clearly in Figure 6, each wiper device 30 comprises a light, four-sided, metal frame having two transverse end members 32, and two longitudinal side members 34 each carrying a flexible wiper member 36 in the form of a flapper composed of textile fabric, chamois leather or other convenient cleaning material. The limbs 20, 22 and 24 respectively have shafts 38, 40 and 42 journaled in them at or near their ends, on each of which shafts the frames of wiper devices are fixed, as shown in Figure 4 and at 44 in Figure 6. These shafts thus constitute rotary carriers for the wiper devices in the guards. Bearings of the shaft 38 are shown at 43 and 45 in Figure 2.

The three shafts 38, 40 and 42 are each arranged to be separately driven by electric motors 46, 48 and 50 respectively, which are respectively mounted on the outside of the three limbs 20, 22 and 24 of the frame. Each wiper motor is arranged to drive its allotted shaft through reduction gearing, as shown at 52 in Figure 2 in connection with the motor 46.

35 A spray pipe 54 of U-shape similar to the U-frame 18 is carried by the latter at the lower edges of the openings in its limbs. This pipe 54 has a number of nozzles 53 (see Figure 6) on each limb spaced apart in the direction of length thereof for directing jets of spray towards the vehicle. A flexible supply pipe 55 for a cleansing liquid, such as water, with or without a detergent, is connected to the spray pipe 54, as shown in Figure 1, and has a control valve 57 as shown in Figure 7.

50 Suspension means arranged to move the carrier 18 with the shafts and wiper devices 30 in it vertically, while the wiper devices are in rotary motion and in contact with the vehicle 10, comprises two sets of flexible suspension members constituted by cables of ropes 56 and 58, one at each side of the frame 18. As shown in Figure 1, the ropes 56 have each one vertical end portion attached to an eye-bracket 60 fixed to the outside of the limb 20 near the lower edge thereof. These ropes pass over rotary members 62 in the form of sheaves or pulleys journaled in brackets 64 mounted on the roof 12, and are joined to a tie rope 68 which, as shown in Figure 7, passes over end sheaves at 70 down to a counterweight 71. The set of ropes 58 running over sheaves 63 is arranged similarly, and is joined to a tie rope 72 connected to the same counterweight 71 which is provided with a guard 73 and is common to all the ropes 56 and 58.

55 Any convenient driving means for operating the supporting cables or ropes and thereby lowering and raising the frame 18 may be provided. As illustrated, an electrically driven winding device 74 has a drum 76 around which a cable 7 is wound. The cable 7 has its ends attached to the rope 72 at spaced positions 8, 9 thereon. The electric motor driving the winding device 74 is indicated at 78 in Figure 8.

Referring to Figure 8, the electrical equipment for controlling the operation of the vehicle-cleaning apparatus comprises two current supply mains 80 and 82, a change-over travel limit switch, designated generally 84, operable by two driver members 86 and 88 (see Figure 7) on a cable, e. g. 68, of one of the sets of supporting cables, two pairs of manually-controlled switches, designated generally 90 and 92, operable by a two-armed manual lever 94, 95, the three wiper motors 46, 48 and 50, each having one terminal connected to the main 82, two contactor devices, designated generally 96 and 98, arranged to control the winch motor 78 and a third contactor device 130 arranged to control the wiper motors 46, 48 and 50. The distance apart of the driver members 86, 88 may be about 15 feet, i. e. rather longer than the height through which it is desired to lift the frame 18.

The travel limit switch 84 comprises two fixed contact-pieces 102 and 104 both connected to the supply main 80, and two movable contact-pieces 106 and 108 operable by a pivotally mounted control arm 110 of inverted T-shape which can be rocked in opposite directions by the driver member 86 and 88, as described hereinafter.

The two pairs of switches 90 and 92 are both controlled by the manually operable lever 93 having two arms 94 and 95, which switches have respectively two fixed contact-pieces 112, 114 and 116, 118 and two movable contact pieces 120, 122 and 124, 126. The fixed contact-pieces 112 and 118 are respectively connected to the movable contact-pieces 108 and 106 of the change-over limit switch 84, and the fixed contact-pieces 114 and 116 are connected together and by way of a winding 128 of a third contactor 130 to the main 80.

The contactor 130 has one set of three terminals 132, 133, 134 connected to one terminal of each of the motors 46, 48 and 50 and has a second set of contact-pieces 136, 137 and 138 connected to the main 80. The other terminals of the motors 46, 48 and 50 are connected to the main 82.

The contactor 96 has one set of contact-pieces 140, 141 and 142, and a second set of contact-pieces 144, 145 and 146. The contact 98 has one set of contact-pieces 148, 149 and 150, and a second set of contact-pieces 152, 153 and 154. The winding 151 of the contactor 96 is connected to the movable contact piece 120 of the switch 90, and by a lead 253 in series with a winding 155 of the contactor 98 which is connected to the movable contact piece 126, the lead 253 being connected to the main 82. These contactors 96 and 98 are connected together and to the motor 78 as follows:

The contact-pieces 144 and 145 are both connected to the contact pieces 152 and 153, and to the main 82, and the contact-pieces 146 and 154 are connected together. The contact-pieces 140 and 148 are connected together by a lead 156 which is connected by a lead 158 to the movable contact-pieces 122 and 124 of the manually operable switches 90 and 92. The lead 156 is also connected to one terminal of the armature of the motor 78. The contact-piece 141 of the contactor 96 is connected by a lead 160 to the contact piece 150 of the contactor 98. The contact-piece 142 of the contactor 96 is connected by a lead 162 to the contact-piece 149 of the contactor 98. This lead 162 is connected by way of the field winding 164 of the motor to the lead 160. The other terminal of the armature of the motor is connected with the main 80 and to the two fixed

contact-pieces 102 and 104 of the limit switch, 84.

As illustrated in Figure 8, the arm 110 of the change-over limit switch 84 carries a wire loop 161 which encircles the cable 68 at a situation between the two driver members 86 and 88. Each of these driver members has a buffer device comprising a collar 163 and a compression spring 165 between it and the adjacent driving device for absorbing shock when either of the driver members operates to change-over the limit switch 84.

The described vehicle cleaning apparatus operates as follows:

Assuming that the frame 18 carrying the wiper devices and spray pipe is moving downwards, at the end of that movement the driver member 88 will rock the arm 110 clockwise as viewed in Figure 8, and it will close the switch 104, 108. The switch 112, 120 is thereby connected in circuit, and when the left-hand arm 94 of the hand-control lever 93 is depressed by an operator, it will close the pair of switches 90. The switch 120, 112 is thereby closed to energize the coil 151 of the contactor 96 which is thus operated. Owing to the switch 114, 122 being closed, the coil 128 of the contacts 130 is energized through the contacts 140, 144 of the operated contactor 96, and thus the contactor 130 is operated, and as a consequence the wiper-driving motors 46, 48, 50 are started. At the same time the energization of the contactor 96 operates the winch motor 78 to rotate the winch drums 76 to wind the supporting cables in the upward direction. The operator is able at any time during the upward movement to return the lever 93 to its inoperative position and thereby stop the wiper motors 46, 48, 50 and the winch motor 78.

After the frame carrying the wipers and spray pipes has reached its upper limit of travel, the travel limit switch 84 is automatically reversed by the driver member 86, the switch 104, 108 is opened and the switch 102, 106 is closed. The switch 118, 126 is then connected in circuit, and when the right-hand arm 95 of the manual control lever 93 is depressed by the operator the wiper motors 46, 48 and 50 will be again energised, the contactor 98 will operate, and the winch motor 78 will be driven in the opposite direction, so that the frame 18 with the wiper devices in rotation will descend. At any time during the downward movement of the frame 18 the operator is able to return the lever 94, 95 to its inoperative position and thereby stop all the motors 46, 48, 50 and 78.

Referring now to Figure 9, this electrical equipment, shown broken away, is similar to that shown in Figure 8, but differs therefrom in the connection of the change-over limit switch. In this equipment a change-over limit switch, designated generally 166, comprises, like the limit switch 84, two fixed contact-pieces 102 and 104, both connected to the supply main 80, and two movable contact-pieces 106 and 108 operable by a pivotally mounted control arm 110 of inverted T-shape which can be rocked in opposite directions by the driver members 86 and 88 in the same manner as described above. In this limit switch the movable contact-pieces 106 and 108 make contact with the fixed contact pieces 102 and 104, respectively, when the control arm 110 is held in its neutral or vertical position by its control spring 168. Consequently the switches 112, 120 and 118, 126, operable by the hand lever 93 are energised. When the control arm 110 is rocked by the driver members 86 and 88 in either direction, one of the movable contact-pieces 106 and 108 breaks con-

tact with its allotted fixed contact-piece, so that one of the manually-operable switches 112, 120 and 118, 126 is de-energised, but the other one remains energised and, when closed by the hand lever 93, energises one of the contactors 96 and 98, so that the wiper carrier 18 is moved down or up. This movement of the carrier 18 can be stopped and reversed by rocking the hand lever 93 to close the other of the two switches controlled by it. Consequently the carrier 18 can be moved up and down repeatedly between its end positions whereby the cleaning operation by the wipers is rendered still more effective.

As shown in Figure 7, the manually operable lever 93 is controllable at an operator's stand 170 by a handle member 172 that is pivoted on the stand and connected by two rods 174 to the lever 93. A handle member 176 on the same stand is connected by a rod 180 to the valve 57, so that the operator can control the flow of water in the supply pipe 55 to the spraying pipe 54. The operator can then arrange that the vehicle is sprayed either before, during or after the operation of the wiper devices.

Non-mechanical indicating means is preferably provided for indicating to an operator at the stand 170 when the vehicle is in its correct endwise position in relation to the wiper carrier 18. As illustrated, this indicating means comprises an electric lamp 182 that is mounted on a stand 184 near the operator's stand 170 and throws a light ray indicated by the broken line 186 on to a photo-sensitive device, such as a photo cell 188, which is connected to a control system comprising an electric circuit containing a thermionic vacuum valve which controls a relay arranged to operate an indicating device, not shown, either visual or acoustic. The arrangement is such that when the vehicle is in its correct operative endwise position in the wiper carrier 18, the light ray 186 is obstructed, so that a signal is given by the control system.

Although the wiper devices are preferably rotated, in some cases provision may be made for giving them a reciprocatory or oscillatory movement while in contact with the vehicle.

In the modified carrier shown in Figures 10, 11 and 12 the end limb 24 and the bracing or tie member 26 of the frame are each divided from the inner surface of the side limb 22 so that the side limb 22 may be moved away from the limb 20. The end limb 24 and the member 26 are each provided at their upper surfaces with a longitudinally extending tube 201 which slidably receives a rod 202 extending laterally from the side limb 22. Each rod 202 is rigidly attached at its end to the upper face of the limb 22 which is thereby constrained to remain parallel to the limb 20, when it is moved away from and towards it, and is also thereby constrained against endwise movement relative to the frame. The end limb 24 and the member 26 are each connected to the side limb 22 by a toggle mechanism 203, 204. Each toggle mechanism 203, 204 comprises two similar toggle levers 205, 206 each comprising two links 207 pivoted together end-to-end at 208. One pair of the toggle levers 205, 206 are pivoted at 210, 211 to the end limb 24 and are pivoted at 212, 213 to the side limb 22. The other pair of toggle levers 205, 206 are pivoted in a similar manner to the member 26 and the side limb 22. Each of the links 207 is of flat strip form and the links 207 lie against the outer end faces of the frame. The pivots connecting the links together and to the frame extend through the links

in a direction parallel to the length of the frame so that when the links of each toggle lever 205, 206 are moved about their pivots to lie collinearly as shown in Figure 12 (i. e. to "make" the toggle) the side limb 22 is at its maximum separation from the side limb 20. The limb 22 is urged towards the limb 20 by means of tension springs 214 connecting the member 22 to the end limb 24 and the member 26, so that when the toggles are "broken" (as shown in Figure 11) the limb 22 moves to a position of minimum separation from the limb 20. Each pair of link-to-link pivots 208 are connected together by a rigid joining link 215 so that each pair of toggle levers 205, 206 may only be "made" and "broken" together. The pivots 212, 213 and the corresponding pair of pivots at the other end of the frame are carried on brackets 216 so that one end of each toggle mechanism projects laterally from the outer side face of the limb 22 and the pivot 212 is connected to its corresponding pivot 217 at the other end of the frame by means of a shaft 218 so that when any toggle is "made" or "broken" all the other toggles are correspondingly "made" or "broken" simultaneously. The shaft 218 is supported at intervals along its length by brackets 220 attached to the outer side face of the limb 22. A stop 221 is provided immediately below each toggle mechanism so that it can only be "broken" by moving the joining links 215 downwards and so that when "made" the toggle passes slightly over centre and the springs consequently tend to hold the toggles against the stops 221 in the "made" positions. The toggles are arranged to be made and broken respectively by two operating chains or cords 222, 223 dependent therefrom, the chain 222 being attached to a link 224 pivoted to one of the joining links 215 so that the toggles are "broken" when the chain 222 is pulled, and the other chain 223 being attached to an arm 225 extending from one of the links radially of the shaft 218 to form a bell-crank lever with that link so that the toggles are "made" when the latter chain is pulled. It will be appreciated that the limb 22 is moved from its position of least separation (shown in full lines in Figure 10) to its position of greater separation (shown in broken lines in Figure 10) by the action of "making" the toggles and is moved in the opposite direction by the action of "breaking" the toggles.

Various modifications may be made in the details of constructions described above without departing from the invention. For example, when the carrier of the wiper devices is of rectangular frame both of its end members, as well as its side members, may be equipped with the described wiper devices. Alternatively, only two side carriers, or only two end carriers having wiper devices may be provided. Also, instead of a shaft on the carrier having a number of wiper devices on it, a single wiper device may extend from end to end thereof. When rotary wiper-devices are provided on the two end links of a rectangular frame the separation of the two end limbs may be adjustable e. g. for cleaning the fronts and backs of trolley buses or trams of different lengths. Limbs may be moved towards or away from one another by means of an electric or other motor operating a rack and pinion or worm and pinion or other suitable mechanism.

I claim:

1. Apparatus for mechanically cleaning a vehicle at a cleaning station, comprising a carrier that is constituted by a frame of U-shape as viewed in plan and has two side limbs arranged

to lie at opposite sides of the vehicle and an end limb arranged to lie at an end of the vehicle, a plurality of shafts mounted one on each limb of the frame, each of which shafts has at least one wiper device mounted on it, means for imparting rotary motion to the shafts, and elevator means arranged to move the frame vertically while the wiper devices are in motion and in contact with the vehicle.

2. Apparatus according to claim 1, wherein each limb of the frame is provided with a pipe having nozzles for delivering a cleansing liquid against the vehicle.

3. Apparatus for mechanically cleaning a vehicle, comprising in combination a superstructure, a carrier, suspension means by which the carrier is suspended from said superstructure and which are operable to effect vertical movement of the carrier, which carrier comprises two substantially horizontally extending limbs lying side by side and spaced apart horizontally along their entire length for the reception of the vehicle between them, at least two wiper devices mounted respectively on the two limbs for wiping movements relative to the limbs and allocated to two opposed sides of the vehicle respectively, means for imparting wiping movements to the wiper devices, which wiper devices are positioned on the limbs to extend, at least during part of their wiping movements, laterally from the limbs into the space between them, and at least one tie member extending between the limbs at one pair of corresponding ends thereof, whereby when a vehicle is positioned between the limbs the wiper devices on the two limbs are at least during the said wiping movements maintained in wiping relation with the said opposed sides of the vehicle by the tie member, and the carrier may, by operation of the suspension means as aforesaid, be moved vertically while the wiper devices are in wiping relation with the vehicle.

4. Apparatus as claimed in claim 3, wherein the length of the tie member is variable, whereby the separation of the two limbs may be varied to permit the apparatus to be employed for cleaning vehicles of different widths.

5. Apparatus as claimed in claim 4, wherein length-adjusting means are provided for adjusting the length of the tie member to either of two pre-selected lengths thereby providing respectively two pre-selected distances of separation between the two limbs.

6. Apparatus as claimed in claim 5, wherein the said length adjusting means comprise a toggle mechanism forming part of the tie member.

7. Apparatus as claimed in claim 6, wherein the said toggle mechanism is an over-centered toggle mechanism, and wherein the two limbs are spring-urged towards one another to relative positions in which they have a pre-selected separation, whereby the two limbs may be urged apart to relative positions in which they have a pre-selected greater separation, against the action of the spring, by operation of the over-centered toggle mechanism to lengthen the tie member and may be held in those positions of greater separation by the over-centered toggle mechanism.

8. Apparatus as claimed in claim 3, wherein the suspension means include flexible suspension members running over pulleys carried by the superstructure.

9. Apparatus as claimed in claim 8, wherein said flexible suspension members are arranged in two sets attached respectively to the two limbs, and wherein the members in each set and their

associated pulleys are spaced apart in the direction of the lengths of said limbs.

10. Apparatus as claimed in claim 9, wherein the suspension members carry at least one counterweight.

11. Apparatus as claimed in claim 10, wherein the suspension means include a reversible motor-driven winding device, and a flexible tension member attached to at least one of the suspension members and wound by the winding device on operation thereof.

12. Apparatus as claimed in claim 11, wherein said flexible tension member is, intermediate in its length, wound round the winding device, and has its ends attached to one of the suspension members at positions spaced along the length thereof.

13. Apparatus as claimed in claim 12, wherein reversing means are provided for reversing the winding device when the carrier arrives at predetermined upper and lower limit positions.

14. Apparatus as claimed in claim 13, wherein the winding device is driven by an electric-motor and wherein there are provided limit switch means, operated automatically when the carrier reaches either of said predetermined upper and lower limit positions, to de-energize said electric motor and to prevent the motor from being re-energized to move the carrier beyond said limit position.

15. Apparatus as claimed in claim 3, wherein said means for imparting wiping movements to the upper devices comprise at least one electric motor carried by the carrier.

16. Apparatus as claimed in claim 3, wherein there is mounted on the carrier at least one delivery pipe for cleansing liquid, having a plurality of nozzles spaced apart in the direction of its length and directed into the space between the limbs for directing said cleansing liquid against the vehicle.

17. Apparatus as claimed in claim 3, wherein the superstructure comprises the roof of a building.

18. Apparatus for mechanically cleaning a vehicle, comprising in combination a superstructure, a carrier, suspension means by which the carrier is suspended from said superstructure and which are operable to effect vertical movement of the carrier, which carrier comprises two substantially horizontally extending limbs lying side by side and spaced apart horizontally along their entire length for the reception of the vehicle between them, at least two rotary wiper devices mounted respectively on the two limbs and allocated to two opposed sides of the vehicle, respectively, means for rotating the wiper devices, which wiper devices are positioned on the limbs to extend, at least when rotated, laterally from the limbs into the space between them, thereby to effect on rotation wiping movements adjacent the limbs and in the space between them, and at least one tie member extending between the limbs at one pair of corresponding ends thereof, whereby when a vehicle is positioned between the limbs the wiper devices on the two limbs are, at least during rotation of the wiper devices, maintained in wiping relation with the said opposed sides of the vehicle by the tie member, and the carrier may, by operation of the suspension means as aforesaid, be moved vertically while the wiper devices are rotated in wiping relation with the vehicle.

19. Apparatus as claimed in claim 18, wherein the wiper devices are carried, respectively, on rotary shafts, which shafts are mounted, respec-

11

tively, for rotation, on the two limbs and extend along the lengths of said limbs.

20. Apparatus as claimed in claim 19, wherein each limb is formed as a guard surrounding the shaft and the wiper device except on the side thereof adjacent the space between the limbs.

21. Apparatus as claimed in claim 20, wherein each wiper device comprises members fixed to and extending longitudinally of the shaft, to which members flexible wiper members are attached.

22. Apparatus as claimed in claim 21, wherein the flexible wiper members comprise flat sheets.

23. Apparatus as claimed in claim 18, wherein two tie members extend respectively between the two pairs of corresponding ends of the limbs.

24. Apparatus for mechanically cleaning a vehicle, comprising in combination, a superstructure, a carrier, suspension means by which the carrier is suspended from the superstructure and which are operable to effect vertical movement of the carrier, which carrier comprises a frame having two substantially horizontally extending side limbs, lying side by side and spaced apart horizontally along their entire length for the reception of the vehicle between them, and an end limb 20 extending between the side limbs at one pair of corresponding ends thereof, at least three wiper devices mounted respectively on the said limbs for wiping movements relative to the limbs and allocated to three sides of the vehicle respectively, 30

12

means for imparting wiping movements to the wiper devices, which wiper devices are positioned on the limbs to extend, at least during part of their wiping movements, laterally from the limbs into the space bounded by them, whereby three sides of a vehicle positioned within the frame may be cleaned simultaneously by operating the suspension means to effect vertical movement of the carrier while the wiper devices have wiping movements imparted to them as aforesaid and are in wiping relation with the said sides of the vehicle.

WILLIAM JOHN MORISON.
